UNITED STATES PATENT OFFICE.

WALTER E. SANDERS, OF TRENTON, NEW JERSEY, ASSIGNOR TO ESSEX RUBBER COMPANY, OF TRENTON, NEW JERSEY, A CORPORATION OF NEW JERSEY.

SHIPPING CONTAINER.

Application filed June 7, 1920. Serial No. 386,976.

To all whom it may concern:

Be it known that I, WALTER E. SANDERS, a citizen of the United States, and a resident of Trenton, county of Mercer, and State of New Jersey, have invented an Improvement in Shipping Containers, of which the following is a specification.

This invention has to do with shipping containers and more particularly it relates to containers employed in the transportation and storage of certain forms of rubber articles.

One of the objects of this invention is to provide a container adapted to carry rubber articles having portions of varied degrees of flexibility, and for supporting the articles in the container so that the more flexible portions thereof are not distorted during shipping, storing or exhibiting.

A selected embodiment of this invention is illustrated in the accompanying drawings wherein,

Figure 1 is a view, partly broken away, of a container with flexible articles mounted therein;

Figure 2 is a view of a frame with the articles mounted thereon;

Figure 3 is a section on the line 3—3 of Fig. 1;

Figure 4 is a view of part of one of the supports or partitions; and

Figure 5 is a detail view showing the method of attaching two of the flexible members to the frame.

In shipping and storing rubber goods having varied degrees of flexibility, it is preferable to support them in containers in a predetermined relation so that the delicate or very flexible portions thereof are not distorted or held under stress. It is well known in the rubber art that a continued distortion or abnormal stress of the delicate portions of rubber articles results in their becoming set and therefore unfit for operation in their normal working position.

A container constituting the selected embodiment of this invention was devised with particular reference to the requirements of shipping and storage of rubber tank balls, and will be hereinafter described in that connection. A typical form of tank ball consists of a conical part 1 of slight flexibility (see Fig. 2), and a semicircular part 2 attached thereto and constructed of rubber of a much higher degree of flexibility. The

part 1 is provided with a stud 3 for attachment purposes which is preferably made with screw threads.

Referring to the drawing, the embodiment of the invention selected for purposes of description is illustrated as a container 4 of suitable material preferably divided into compartments, each adapted to receive a single tank ball. Herein the container consists of a frame 5 for supporting the tank balls 6, and supports 7 for holding the frame in a box 8 in predetermined position in relation to the sides of the box. The supports are preferably formed as interlocking partitions to provide compartments for the articles and to maintain the articles out of contact with the box.

In assembling the tank balls in the container they are first attached to the frame 5 which is of sufficient size and strength to support the full weight of several of the tank balls. The means for attaching the tank balls to the frame preferably consists of a screw threaded member held in or by the frame, and upon which the stud of the tank ball is screwed until the less flexible part 1 of the ball is firmly drawn against the frame. A simple and effective connection is secured by providing a screw threaded stud 9 which is adapted to pass through one of the apertures 10 in the frame, and which has two tank balls screwed thereon from opposite sides of the frame 5 until the conical parts 1 pinch the frame between them and in this manner the tank balls are held rigid with the frame.

This frame with the tank balls mounted thereon is next placed in the outer box 8 which is preferably collapsible and provided with flaps for closing over its ends. The frame is supported in the box so that the more flexible portions of the tank balls are out of contact with the inner walls thereof, and are therefore not distorted or put under stress. Any suitable support may be provided to position the frame 5 in predetermined relation to the inner surfaces of box 8, the same being herein illustrated as partitions 7 (see Fig. 4) which interlock and form separate compartments for each tank ball. The width of the partitions is made greater than the height of the tank balls so that the more flexible parts thereof do not contact with the box.

In making use of this container for shipping, storing and exhibiting purposes, the

substantially non-flexible part 1 of the tank ball is employed to support the weight of the whole ball irrespective of the position in which the container may be placed, and the 5 delicate or flexible part thereof is so supported that it is not distorted or put under stress. Should the frame sag or have the tank balls loosely mounted thereon there will be no injury to that part of the tank ball 10 which is repeatedly flexed under normal operation as the partitions will assist in supporting by contacting with the rim of the substantially non-flexible part 1.

This collapsible container having the 15 frame and the partitions separately movable from the box is advantageously used to exhibit the rubber articles as the frame may be withdrawn and one set of partitions removed, as illustrated in Fig. 2.

20 This invention may be variously embodied and the particular form of the invention shown may be varied within the scope of the subjoined claims.

I claim:

- 25 1. In a container the combination of an apertured frame for supporting resilient articles, means associated with said articles and said frame to hold two articles on said frame on opposite sides thereof and opposite 30 each other, a portable flexible box to hold said frame and articles, and interlocked partitions associated with said frame and said articles to retain said frame in predetermined position.
- 35 2. In a container for shipping and ex-

hibiting rubber goods the combination of a portable outside box, an apertured frame received in said box and contacting with opposite sides thereof said frame having tank balls firmly pressed against each side there- 40 of by having them affixed to screw threaded studs passing through the apertures, removable interlocked partitions contacting with said box and said frame for holding said tank balls separate and out of contact with 45 said box.

3. A package for resilient or fragile articles comprising an article supporting partition, means passing through said partition and cooperating with an article on each side 50 thereof to secure said opposed articles to the partition, and an article separating partition connected with said article supporting partition and positioned between adjacent pairs of opposed articles supported thereon. 55

4. A package for resilient or fragile articles comprising a container, a removable article supporting partition therein, a removable partition cooperating with the container to maintain the article supporting 60 partition in operative position therein, and means passing through the article supporting partition and cooperating with an article at each side thereof to secure said articles to said partition.

In testimony whereof, I have signed my name to this specification this third day of June, 1920.

WALTER E. SANDERS.
